UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

METHOD OF FORMING BRAKE-BEAM TRUNNIONS.

Application filed April 23, 1920. Serial No. 377,155.

To all whom it may concern:

Be it known that I, LOREN L. WHITNEY, a citizen of the United States, residing at Hammond, in the county of Lake and State 5 of Indiana, have invented certain new and useful Improvements in Methods of Forming Brake-Beam Trunnions, of which the following is a specification.

This invention relates to a method for 10 forming brake beam trunnions.

An object of this invention is to simplify and improve the methods of forming brake beam trunnions, reducing the cost of manufacture and at the same time providing a 15 brake beam trunnion adapted to meet the requirements for successful commercial use.

This and other objects are accomplished by means of the method disclosed on the accompanying sheet of drawings, in which—

20 Figures 1 and 2 are end and top plan views, respectively, of a brake beam blank;

Figures 3 and 4 are end and top plan views of the same blank after being upset;

25 Figures 5 and 6 are end and top plan views of the same blank after being further upset;

Figures 7 and 8 are end and top plan views of the blank after being still further upset, the blank now being shown as provided with sufficient built-up stock necessary 30 for succeeding operations;

Figures 9 and 10 are end and top plan views of the same blank after the end has been drawn out a predetermined amount:

35 Figures 11 and 12 are end and top plan views of the same blank after being upset a predetermined amount to approach the final shape of the trunnion, there being a fin or flash left after this operation;

40 Figures 13 and 14 are end and top plan views of the same blank after the flash has been removed; and

Figures 15 and 16 are end and top plan 45 views of the finished brake beam trunnion.

It will be noted from the figures of the drawings that only a portion of the brake beam has been shown, it being understood that the opposite end of same will appear as the end shown.

50 The type of brake beam shown is of the plain I section. In forming the trunnion a commercial brake beam blank 10 of I section is provided, as shown in Figures 1 and 2. The end of the blank is then heated and

upset a predetermined amount in any suitable well-known type of upsetting machine, giving the end of the blank an appearance as shown in Figures 3 and 4. The end of the blank is then upset an increased amount as shown in Figures 5 and 6, and then subjected to a third upsetting action, giving the end of the blank a built-up portion 11 of stock, as shown in Figures 7 and 8, preparatory to the succeeding operations. It will be understood that during all of these upsetting actions the blank 10 is properly gripped between suitable dies to control the upsetting at the proper points. The end of the beam is then drawn out between suitable dies on a steam hammer to the form shown in Figures 9 and 10, it being noted that the end 12 of the blank is rounded, which is the first rounding action given to the blank. The end of the blank is then upset a fourth time between suitable dies for shortening the 75 trunnion portion 13 and forming a shoulder 14, it being noted that a fin or flash 15 is left around the trunnion which is caused by the junction of the dies, as shown in Figures 11 and 12. In the next operation the fin or flash 15 is removed, as shown in Figures 13 and 14, whereupon the blank is given its fifth upsetting action to give the trunnion 80 85 its final shape, as shown in Figures 15 and 16.

It is my intention to cover all modifications of the invention falling within the spirit and scope of the following claims.

I claim:

1. The method of forming a brake beam 90 trunnion consisting in providing a blank, heating same, upsetting said blank to build up the stock for the trunnion, drawing out said upset portion to approach the final trunnion shape, and then upsetting the 95 drawn-out portion to give the trunnion its final shape.

2. The method of forming a brake beam trunnion consisting in providing a blank, heating same, upsetting said blank to build up the stock for the trunnion, drawing out 100 said upset portion to approach the final trunnion shape, and then treating the drawn-out portion to give the trunnion its final shape.

Signed at Hammond, Ind., this 22 day of April, 1920.

LOREN L. WHITNEY.
